ABSTRACT: A rock drill rod which has a reduced diameter portion at either or both ends. The main portion of the rod is of constant diameter and threaded throughout its length. The reduced diameter portion is threaded substantially throughout its length. A drill bit is secured to the reduced diameter end and is dimensioned to drill a hole slightly larger than the diameter of the drill rod.

ROCK DRILL ROD

BACKGROUND OF THE INVENTION

This invention relates to rock drill rods and a rock drill rod and drill bit system used in drilling small diameter holes. With respect to small diameter boreholes, the drill rod is an improvement of the U.S. Pat. Application of J. D. Ditson and James F. Cantrel, Ser. No. 525,009, now U.S. Pat. No. 3,424,479, filed Jan. 11, 1968.

In modern drilling practices, there is an increasing use of long, small diameter holes.

One problem encountered in drilling long, small diameter holes is the lack of rigidity of the drill rod. As a percussive blow is delivered to the drill rod and as weight is applied to the drill rod, the rod bends. This bending which occurs results in an increase in stress in the rod and a crooked hole being drilled.

One method of overcoming this bending is to attach a centralizer to the drilling machine. This addition can be expensive and is not practical in all drilling situations. Another method of reducing this bending is to make the drill rod more rigid. In general, the rigidity of the drill rod can best be increased by increasing the diameter of the rod. The rod must, of course, follow the drill bit down the hole being drilled, and there must be sufficient clearance between the borewall and drill rod to permit cuttings to pass out of the hole. The diameter of the drill rod is therefore limited by the size of the hole being drilled.

The threaded socket on the drill bits which are used for drilling small diameter holes is too small to permit adequate attachment of the bit to a conventional constant diameter rod which is rigid enough to withstand the forces which cause bending of the rod.

Prior drill rods which have sufficient rigidity to prevent bending while permitting the attachment of small drill bits have the disadvantage that once they fail, the rod has either lost its usefulness or must be returned to the shop for reconditioning such as for rethreading. A drill rod of this type is normally 10 or 12 feet long. If the end of a conventional rod which permits attachment of a small hole bit is broken, the remaining length of the rod cannot be used. Since this is where rod failure is most likely to occur, use of prior drill rods which provide ample rigidity yet permit small hole drilling are not economical.

SUMMARY

It is therefore the principal object of this invention to provide a reconditionable drill rod which is sufficiently rigid to reduce the tendency of the rod to bend yet is capable of being used in drilling small diameter holes.

It is a further object of this invention to provide a drill rod and drill bit system suitable for drilling long, small diameter holes.

It is another object of this invention to provide a drill rod which is capable of being reconditioned in the field should failure occur.

It is still a further object of this invention to provide a drill rod which has prolonged economic life.

In general, the foregoing and other objects will be carried out by providing a drill rod comprising an elongated body having a first diameter portion and a second, reduced diameter portion at at least one end thereof and a bore axially therethrough; said first diameter portion having an attachment thread extending substantially the entire length thereof; and said second, reduced diameter portion having an attachment thread extending from the end of the drill rod toward the intersection of the first and second portions for a distance sufficient to permit a drill bit to be threadedly secured thereof.

BRIEF DESCRIPTION OF THE DRAWING

The invention will be described in connection with the annexed drawing wherein:

FIG. 1 is a plan view of a drilling machine employing one embodiment of the present invention to drill a hole;

FIG. 2 is a plan view of one embodiment of the drill rod of the present invention;

FIG. 3 is a plan view of a modification of the present invention with certain parts in section; and

FIG. 4 is a plan view on a smaller scale of the drill rod of FIG. 3 as it is used for long hole drilling.

DESCRIPTION OF THE PREFERRED EMBODIMENTS

The drill rod and drill rod and drill bit system of the present invention will be used in combination with a drilling machine such as that generally indicated at 1 in FIG. 1. The drill rod 2 is connected to the drill 1 in a manner well-known in the art. The drill delivers an impact to the drill rod and rotates the drill rod. The impact is transferred to a drill bit 16 to drill a hole 17 in rock or the like. The operation of the drill rod is well-known in the art and need not be described.

Referring to FIG. 2, the drill rod 2 includes an elongated body having a first portion 3 which extends for almost the entire length of the drill rod. The first portion 3 is of substantially constant diameter throughout its entire length. This portion is provided with a roll formed thread 4 which extends circumferentially around the drill rod throughout the length of the first portion 3 in the same manner as the drill rod shown in U.S. Pat. Application Ser. No. 525,009. The thread 4 is characterized by a lubrication groove 5 which extends the length of the first portion 3. The end 6 of the rod is dimensioned to fit the coupling on a conventional drilling machine.

20 A second, reduced diameter portion 8 is provided at one end of the drill rod 2. A roll formed thread 9 is wound circumferentially around the reduced diameter portion 8 from the end 11 of the rod toward the first portion 3 of the drill rod. As with the thread 4, a grease groove 10 extends for the length of the thread 9. For certain applications and methods of constructing the drill rod, it may be desirable to eliminate the grease grooves 5 and 10.

25 Because the thread 9 is roll formed, the reduced diameter portion 8 may be threaded all the way to the intersection of the first and second portions. In order to more clearly show the separation between the two portions 3 and 8, a space 12 on the reduced diameter portion 8 has been shown without threads. In the embodiment shown the lead of the thread 4 is the same as the lead of the thread 9 so that standard drill bits 35 and couplings may be used. In certain applications, it may be desirable to use a different thread on the reduced diameter portion than on the portion 3 of the rod.

30 The drill rod is provided with a bore 15 axially therethrough for conducting blow air for removing cuttings from the hole being drilled. As indicated at 14, the bore 15 is reduced in diameter at the reduced portion 8. This reduction in the size of the bore insures that the wall thickness remains substantially constant throughout the length of the rod and thus increases the strength of the rod. If the bore 15 were of constant size 40 throughout the rod length, the wall thickness of the reduced diameter portion 8 would be reduced to the point where the likelihood of rod failure at the portion 8 would be greatly increased.

35 The reduced diameter portion on the end of the drill rod permits small diameter holes to be drilled while insuring greater rigidity of the drill rod. As shown in FIG. 1, a drill bit 16 is threadedly secured to the reduced diameter portion of the drill rod 2. The drill bit 16 is dimensioned to drill a hole which is usually between one-eighth and one-quarter inch larger than the diameter of the enlarged portion 3 of the drill rod although such dimensions are not intended to be a limiting factor. The threaded socket on bits for drilling small diameter holes will be necessarily small. The reduced diameter portion 45 8 is small enough to permit the drill bit to be secured thereto while the larger diameter portion 3 provides the necessary rigidity.

40 By way of example, the first portion 3 of the drill rod will be 1 $\frac{1}{8}$ inches in diameter and the reduced diameter portion 8 will be 1 $\frac{1}{4}$ inches in diameter. Normally, a 1 $\frac{1}{8}$ inch drill bit will be 45 70 75 77 78 79 80 81 82 83 84 85 86 87 88 89 90 91 92 93 94 95 96 97 98 99 100 101 102 103 104 105 106 107 108 109 110 111 112 113 114 115 116 117 secured to the reduced diameter portion 8 although a bit as small as 1 $\frac{5}{8}$ inches may be used.

Although the length of the reduced diameter portion may vary from as long as more than half the overall length of the rod to as short as a few inches, it has been found that a maximum length of about 1 foot provides the optimum performance as far as rigidity and rod life are concerned. The reduced diameter portion is preferably threaded a distance at least twice the length necessary to attach a drill bit to the rod. The continuous threading of the reduced diameter portion 8 permits a broken end to be squared off and the drill bit reattached. Because the portion 3 of the drill rod is continuously threaded and the overall length of the rod is usually 10 or 12 feet, should the rod break so that the reduced diameter portion is no longer useful, an end of portion 3 of the rod may be squared off and a drill bit used for drilling larger diameter holes may be secured to the rod.

In FIGS. 3 and 4, I have shown a modification of the drill rod of the present invention which is designed for drilling long holes of small diameter where it is necessary to use more than one drill rod. In order to provide rigidity, the rod has a first portion 21 which has a diameter sufficiently large to substantially reduce the tendency of the rod to bend. The portion 21 is provided with threads 22 and a grease groove 23 extending throughout its length. Reduced diameter portions 24 are provided at each end of the rod. Each is provided with threads 25 and a grease groove 26 extending substantially entirely from the end 27 to the intersection between the portions 21 and 24. A nonthreaded portion 28 is shown for clarity.

The reduced diameter portions 24 may be used for attaching a drill bit 16 to the drill rod or coupling two drill rods together as shown in FIG. 4. The coupling 30 may be of the type shown in the U.S. Pat. Application of J. D. Ditson and James F. Cantrel, Ser. No. 525,009. Use of a reduced diameter portion at the point where two rods are to be coupled together permits the use of a coupling having a diameter small enough to follow the drill rod down the hole.

As is the case with the embodiment of FIG. 1 and 2, the portions 24 are sufficiently long to permit reattachment of the drill bit or coupling should breakage occur. Continuous threading of the portion 21 permits the rod to be used for drilling larger diameter holes should the reduced diameter portions become useless. The lead 1 of the two threads 22 and 25 are substantially identical.

From the foregoing it is apparent that the objects of this invention have been carried out. The rod provides the rigidity lacking in prior art drill rods used in drilling small diameter holes. The continuous threading of the rod prolongs the useful life of the drill rod and permits field maintenance should breakage occur. The threads on both the large and small diameter portions are standard to permit the use of a standard drill bit and standard coupling. Although in the embodiment shown both threads are roll formed, in certain applications, it may be desirable to use some other method of forming on of the threads.

I claim:

1. A drill rod comprising an elongated body having a first diameter portion and a second, reduced diameter portion at least one end thereof and a bore axially therethrough; said first diameter having an attachment thread extending substantially the entire length thereof; and said second, reduced diameter portion having an attachment thread extending from the end of the drill rod toward the intersection of the first and second portions for a distance sufficient to permit a drill bit to be threadedly secured thereto.
2. The drill rod of claim 1 wherein there is a reduced diameter portion at each end of the drill rod.
3. The drill rod of claim 1 wherein said bore is reduced in diameter at said second, reduced diameter portion.
4. A drill rod comprising an elongated body having a first diameter portion and a second, reduced diameter portion at least one end thereof and a bore axially therethrough;

said first diameter having portion attachment thread extending substantially the entire length thereof;

said second, reduced diameter portion having an attachment thread extending from the end of the drill rod toward the intersection of the first and second portions for a distance sufficient to permit a drill bit to be threadedly secured thereto; and wherein the lead of the thread on said first portion is substantially the same as the lead of the thread on said second portion and at least one of said threads is roll formed.

5. The drill rod of claim 4 wherein said second portion is threaded substantially completely to the intersection of said first and second portions and said second portion is no longer than one-tenth the length of the drill rod.

10 6. A rock drill rod and drill bit system comprising: a drill rod having a first portion and a second, reduced diameter portion at one end thereof;

said first portion having an attachment thread which extends circumferentially around the first portion throughout its length;

said second, reduced diameter portion having an attachment thread which extends circumferentially around the second portion substantially completely throughout its length; and

15 a drill bit secured to the second portion of the drill rod and dimensioned to bore a hole having a diameter larger than the diameter of said first portion.

20 7. The drill rod and drill bit system of claim 6 wherein said drill bit is dimensioned to bore a hole at least one-eighth inch larger than the diameter of said first portion.

25 8. The drill rod and drill bit system of claim 6 wherein said drill rod is provided with a bore axially therethrough and said bore is reduced in diameter at said second portion.

30 9. The drill rod and drill bit system of claim 8 wherein said second portion is threaded for a distance which is at least twice as long as the length of thread needed to secure said drill bit thereto.

35 10. A rock drill rod and drill bit system comprising: a drill rod having a first portion and a second, reduced diameter portion at one end thereof;

said first portion having an attachment thread which extends circumferentially around the first portion throughout its length;

said second, reduced diameter portion having an attachment thread which extends circumferentially around the second portion substantially completely throughout its length;

40 a drill bit secured to the second portion of the drill rod and dimensioned to bore a hole having a diameter larger than the diameter of said first portion; and wherein the lead of the thread on said first portion is the same as the lead of the thread on said second portion.

45 11. The drill rod and drill bit system of claim 10 wherein both of said threads are roll formed.

50 12. A rock drill rod and drill bit system comprising: a drill rod having a first portion and a second, reduced diameter portion at one end thereof;

said first portion having an attachment thread which extends circumferentially around the first portion throughout its length;

said second, reduced diameter portion having an attachment thread which extends circumferentially around the second portion substantially completely throughout its length;

55 a drill bit secured to the second portion of the drill rod and dimensioned to bore a hole having a diameter larger than the diameter of said first portion; wherein

said drill bit is dimensioned to bore a hole at least one-eighth larger than the diameter of said first portion; and wherein the lead of the thread on said first portion is the same as the lead of the thread on said second portion and at least one of said threads is roll formed.
